PIPERAZINE SALT OF PHYTIC ACID

Jack Bernstein, New Brunswick, and William A. Lott, Maplewood, N.J., assignors to Olin Mathieson Chemical Corporation, New York, N.Y., a corporation of Virginia

No Drawing. Filed Apr. 10, 1959, Ser. No. 805,375
1 Claim. (Cl. 260—268)

This invention relates to new urolitholytic agents and more particularly to new compounds which are the salts of phytic acid and non-toxic organic bases. 10

Recently it has been found that sodium phytate is of use in lowering urinary calcium, thereby reducing the incidence of kidney stones in susceptible persons. To be effective in the reduction of renal calculi, however, relatively large dosages of the medicament are required, usually in the range of about 5 grams to about 20 grams daily. Unfortunately persons who have a history of kidney stones are often afflicted with other physiological conditions, such as hypertension or related cardiac conditions, which counterindicate the ingestion of large quantities of sodium ion. Hence, sodium phytate suffers the disadvantage of requiring the administration of large quantities of sodium ions to patients from whom sodium (e.g. salt) should be kept. 15

It is an object of this invention, therefore, to provide a new class of chemical compounds which are useful in the treatment and/or prevention of renal calculi and which are less likely to cause untoward side-effects.

This object is achieved by the compounds of this invention which comprise the salts of phytic acid and non-toxic organic bases, preferably organic bases which yield water-soluble salts with phytic acid, such as non-toxic organic bases of less than ten carbon atoms, as exemplified by the non-toxic lower alkyl amines, di(lower alkyl) amines, hydroxy(lower alkyl) amines (e.g. β -aminoethanol and 1-amino-2-propanol), di-hydroxy(lower alkyl) amines, tri-hydroxy(lower alkyl) amines (e.g. triethanolamine and tri-isopropanolamine), amino-lower alkanediols, amino-lower alkanepolymers (e.g. N-methyl-glucamine), hydroxy-poly-alkylene-polyamines [e.g. N-(hydroxyethyl)diethylenetri-amine and N-(hydroxyethyl)propylenediamine], ester and ether derivatives of such hydroxy containing amines (e.g. acetylethanolamine and 2-aminoethoxyethanol), poly-alkylene-polyamines (e.g. triethylene-tetramine), monocyclic N-heterocyclic compounds, such as piperazine and 4-(aminopropyl)morpholine, and quaternary ammonium salts such as choline. (By salts of phytic acid and non-toxic organic bases is meant not only salts wherein all twelve acidic hydrogen ions of the phytic acid are combined with organic bases, but also salts wherein the phytic acid is partially neutralized and salts wherein some of the phosphate groups are neutralized with inorganic bases, such as alkali metals.)

To prepare the compounds of this invention: (a) phytic acid is reacted with the desired non-toxic organic base to yield the fully or partially neutralized corresponding phytate derivative; or (b) by metathesis, an inorganic salt of phytic acid, such as an alkali metal salt (e.g. sodium phytate) is treated with the desired non-toxic organic base or an inorganic acid-addition salt thereof (e.g. hydrochloride) to yield a phytic acid derivative fully or partially neutralized with the desired non-toxic organic base; or (c) phytic acid is treated with an inorganic acid salt of

2

the desired non-toxic organic base. If sodium phytate is employed as the reactant, then preferably all or substantially all of the sodium ion is replaced thereby minimizing the sodium content of the final phytate product.

5 The compounds of this invention are useful in the treatment and/or prevention of renal calculi, for which purpose they are administered perorally in a daily dose of about 5 grams to about 20 grams. The compounds of this invention can be formulated in the usual manner to give peroral compositions, such as tablets, capsules or powders, or may be suspended or dissolved in customary manner to give elixers, syrups, etc.

The following examples illustrate the invention (all temperatures being centigrade):

EXAMPLE 1

Phytic acid, salt with 3 moles of piperazine hexahydrate

To 200 cc. of a 40% aqueous solution of phytic acid is added 97 g. (0.5 M) of piperazine hexahydrate. The resulting solution has a pH of 3.7 and a total volume of 275 cc. 100 cc. of this solution is diluted to 800 cc. (pH 4.2) and freeze-dried to yield about 39 g. of product melting at about 90–100°.

25

EXAMPLE 2

Phytic acid, salt with 6 moles of piperazine decahydrate

To 200 cc. of 40% aqueous solution of phytic acid is added 194 g. (1.0 M) of piperazine hexahydrate. The solution has a pH of 7.4 and a total volume of 360 cc. After standing a few minutes crystallization occurs. Then 500 cc. of methanol is added and the mixture allowed to stand. The solid is filtered and washed with methanol to yield about 159 g. of product melting at about 135–140° with decomposition.

35

EXAMPLE 3

Phytic acid, salt with 6 moles of choline

To 100 cc. of 45% aqueous solution of choline bicarbonate is added 64 cc. of a 40% aqueous solution of phytic acid. The pH of the resulting solution is 5.1 and the total volume is 155 cc. The product can be isolated by diluting 80 cc. of the solution to 500 cc. with water (pH 5.3) and freeze-drying to yield a gummy solid.

45

EXAMPLE 4

Phytic acid, salt with β -aminoethanol

To 100 cc. of a 40% aqueous solution of phytic acid is added 51.2 g. (0.84 M) of β -aminoethanol. The pH of the resulting solution is 6.4 and the total volume is 170 cc. 100 cc. of this solution is diluted to 800 cc. and freeze-dried to yield the product as a viscous oil.

55

EXAMPLE 5

Phytic acid, salt with triethanol amine

To a solution of 92.4 grams of sodium phytate in 100 ml. of water, there is added a solution of 220 grams triethanol amine hydrochloride in 500 ml. of water. The solution is then freeze-dried and the residue suspended in 500 ml. of absolute ethanol. The insoluble sodium chloride is removed by filtration and the filtrate is concentrated to dryness under reduced pressure to give the desired product as a viscous oil.

3
EXAMPLE 6*Phytic acid, salt with N-methylglucamine*

To a solution of 56.4 grams of phytic acid in 100 ml. of water there is added a solution of 240 grams of N-methylglucamine in 500 ml. of water. The solution is then freeze-dried to give the desired product as a viscous oil.

The invention may be variously otherwise embodied within the scope of the appended claim.

What is claimed is:

The piperazine salt of phytic acid.
